Attorney.

UNITED STATES PATENT OFFICE.

EDWIN A. WOOD, OF UTICA, NEW YORK.

STEAM-HEATING DEVICE.

SPECIFICATION forming part of Letters Patent No. 311,704, dated February 3, 1885.

Application filed September 13, 1884. (No model.)

To all whom it may concern:

Be it known that I, E. A. Wood, a citizen of the United States, residing at Utica, in the county of Oneida and State of New York, have 5 invented certain new and useful Improvements in Steam-Heating Devices, of which the following is a specification, reference being had therein to the accompanying drawing.

My invention relates to improvements in 10 devices for heating churches, public halls, cars, &c., by steam.

The object of my invention is to provide a 15 shield or deflector for steam-pipes, which are placed horizontally under the pews and seats of churches, public halls, railway-cars, and other places, so that the heated air will not rise into the face of the occupant of the seat, but will be deflected forward against the feet and lower extremities of the person in the seat 20 in front.

My invention therefore consists in covering 25 the upper surface of the horizontal heating-pipes with a board or iron plate placed at an angle in such a manner that it will deflect or turn the current of heated air forward and upward, instead of allowing it to rise directly from the pipe into the face of the occupant of the next seat in the rear.

In the drawing I have shown an end view 30 of a church-pew with a portion broken away to show the pipes more clearly.

In heating and warming churches, public 35 halls, railway-cars, &c., by steam, the pipes are frequently placed in a horizontal position under the seats, and, as they are exposed to view, their appearance is unsightly. Furthermore, the occupants of the pews will naturally place their feet on the hot pipes, and the odor of 40 burned rubber or leather tends to bring this style of heating into disrepute, especially as the heated air rises and brings these offensive odors directly into the face of the occupant of the pew next in the rear. To overcome these 45 objections I employ the following devices, which I will now proceed to describe:

A is the seat or pew, which may be of the ordinary or any desirable construction.

B indicates the steam pipe or pipes, arranged horizontally underneath the seat, and 50 are supported at intervals a short distance

from the floor by the brackets or standards C. The upper ends of the standards or brackets are inclined, as shown at a, to receive and support a board or iron plate, D. The board or plate may be supported in grooves formed 55 in the sides of the bracket, or on cleats secured to the sides of the seat-supports. The board or plate D is of sufficient width to serve as a foot-rest, and also to cover the steam-pipe, and being inclined upward, as shown, serves 60 to deflect or direct the hot air forward under the seat, while the pendent board E serves to prevent the hot air from coming up back of the seat into the face of the occupant of the adjacent pew in the rear. The pendent 65 board E may be dispensed with. This objectionable feature, heretofore mentioned, is specially noticeable when the occupants of the pew lean forward to rest their heads on the seat in front of them, as is usually the case 70 during prayer-service; but by the use of the deflecting-board the hot-air currents in their ascent are thrown forward onto the lower extremities of the occupants of the pew, and in this way the air is disseminated and parts 75 with most of its heat before it rises to the top of the seat, and does not come in direct contact with the faces of the occupants of the pew in a highly-heated condition.

Having thus described my invention, what I 80 claim, and desire to secure by Letters Patent, is—

1. In a steam-heating device for churches, 85 halls, cars, &c., a horizontal pipe or pipes arranged underneath the pew or seat, in combination with an inclined board or plate located above the pipe or pipes, as described, whereby the heated air is deflected forward under the seat, as set forth.

2. In a device for heating churches, halls, 90 cars, &c., a pipe or series of pipes arranged underneath the seats, supported by suitable brackets, in combination with a deflecting-board, as set forth.

In testimony whereof I affix my signature in 95 presence of two witnesses.

EDWIN A. WOOD.
